UNITED STATES PATENT OFFICE.

COMEGYS C. LUSBY, OF PHILADELPHIA, PENNSYLVANIA, ASSIGNOR OF
ONE-HALF TO JOSEPH A. CRAMP, OF SAME PLACE.

HANDPIECE.

SPECIFICATION forming part of Letters Patent No. 655,498, dated August 7, 1900.

Application filed August 18, 1899. Serial No. 727,638. (No model.)

To all whom it may concern:

Be it known that I, COMEGYS C. LUSBY, of Philadelphia, in the State of Pennsylvania, have invented certain new and useful Improvements in Handpieces, whereof the following is a specification, reference being had to the accompanying drawings.

My invention relates to chuck devices arranged upon the extremity of a flexible rotary shaft and to detachably clamp a drill or similar instrument, so as to rotate the same in the hand of the operator. When such devices are used in dental surgery, the interior working parts become charged with bacteria and are a source of contamination to the instruments which are successively inserted therein.

It is one of the objects of my invention to provide a handpiece peculiarly adapted for the use aforesaid in that the interior working parts are readily accessible even to an unskilled operator and may be conveniently separated for sterilization.

My invention comprises a tubular spindle composed of separable members, clamping mechanism mounted in said spindle and arranged to be readily detached therefrom, and other details of construction hereinafter more definitely specified and claimed.

In the accompanying drawings, Figure 1 is a longitudinal sectional view of a convenient form of my invention, the parts being in position to clamp the instrument inserted therein. Figs. 2 and 3 are top plan views of the

respective telescoping members of the spindle shown in Fig. 1. Fig. 4 is a side elevation of the adjustable plunger shown in Fig. 1. Figs. 5, 6, and 7 are cross-sectional views taken, respectively, on the lines 5 5, 6 6, and

7 7 shown in Fig. 1.

The exterior casing of the handpiece comprises a front member A and a rear member A', said two parts being in threaded engagement with the sleeve A², respectively, at a and a'. The hollow spindle in which the instrument is clamped is composed of the telescoping members C and C' and is mounted for rotation in the cone-bearing a³ of the casing member A and in the sleeve A². In order to secure the spindle against longitudinal displacement, the rearward extremity

c thereof, which extends through the sleeve A², is of reduced diameter, the shoulder c' being provided with the washer c² to bear against the front face of said sleeve A², and the splined collar c³ is presented against the rear face of said sleeve by means of the nut c¹ in threaded engagement with said extremity c of the spindle. The front member C' of said spindle fits within the body portion C thereof and is secured against rotation therein by the engagement of the lug c⁵ in the recess c⁶. Within the member C' of said spindle is mounted the resilient split tubular chuck D, which bears at its forward end upon the cone-bearing c⁷ in the spindle member C' and is engaged at its rear extremity in the hollow conical end e of the plunger E. Said plunger E is provided with a rear extension e', longitudinally adjustable in threaded engagement therewith, whereby the effective length of said plunger may be varied to compensate for wear of the parts, &c.

The rear extremity of the spindle member C' is notched at c⁸ to register with the slot c⁹ in the body C, and the clamping-lever F being entered in said slot and notch with its trunnions f in the trunnion-seats c¹⁰ of both of said spindle members serves to secure the same against relative longitudinal displacement. The arm f' of said lever F bears upon the extension e' of the plunger E, and the latter is so adjusted that the arm f² of said lever is normally projected beyond the circumference of the spindle.

Within the casing A and surrounding the clamping-lever F is a slidable sleeve G, in which the bearing-ring g is mounted for free rotation between the shoulders g' and g². The sleeve G may be grasped through the openings a³ in the casing member A, and to facilitate its manipulation its outer circumference is ridged, as indicated at g³.

The operation of the device is as follows: The sleeve G being in its forward position, the chuck D is permitted to expand, thrusting the plunger E rearwardly against the arm f' of the lever F and projecting the arm f² of the latter outwardly from the slot c⁹. The instrument X is inserted, with the parts in the position aforesaid, and the sleeve G is grasped through the openings a³ and drawn

rearwardly, whereupon the bearing-ring g in said sleeve riding over the arm f^2 of the lever F thrusts the arm f' of said lever against the extension e' of the plunger E and ⁵ presses the chuck D between the conical end e of the plunger E and the conical seat c' in the spindle member C' , thus clamping the instrument X securely with respect to the spindle. With the parts in the clamped position ¹⁰ described the spindle C , together with the tool X , &c., may be rotated in its bearings in the casing A by means of the shaft B , upon which it is secured, the bearing-ring g being rotated with said spindle between the ¹⁵ shoulders g' and g^2 in the sleeve G . The latter remaining stationary in the casing A prevents accidental return of the parts to the released position. To release the instrument X , the sleeve G is grasped through the openings a^3 and thrust forward, whereupon the resilient chuck D is permitted to expand, as aforesaid, and the instrument may be freely withdrawn.

When it is desired to remove the internal ²⁰ working parts of the handpiece for any purpose, such as the sterilization hereinbefore referred to, the front casing member C is unscrewed from its connection with the sleeve A^2 , carrying with it the sleeve G . The lever F thus uncovered may be lifted from the slot ²⁵ c^3 , and the spindle parts $C C'$, which, as above noted, are relatively secured by the trunnions f of the lever F , are thus disengaged. The spindle member C' being thereupon withdrawn from the spindle-body C , the plunger E and chuck D may be shaken from said member C' . It is to be noted that all of the ³⁰ working parts which may be charged with bacteria are thus readily accessible without the employment of skilled labor to manipulate them.

For the purpose of dismantling and assembling the parts as aforesaid the casing-sleeve A^2 may be considered as a fixture with respect to the casing member A' , being secured therein by the set-screw a^4 . It is to be noted, however, that said set-screw bears upon a smooth cylindrical portion a^5 of said sleeve and that the relative longitudinal position of ⁴⁰ said sleeve A^2 in the casing member A' may be adjusted so that as the spindle C wears in its bearings the front casing member A may be screwed farther upon the sleeve A^2 .

to bring the cone-bearing a^2 in the forward end of the casing in proper relation with the ⁵⁵ forward end of said spindle. Wear of the spindle in the sleeve A^2 may of course be compensated for by longitudinal adjustment of the collar c^3 and nut c^4 .

I do not desire to limit myself to the precise details of construction which I have shown and described, as it is obvious that various modifications may be made therein without departing from the spirit of my invention. ⁶⁰

I claim—

1. In a handpiece, the combination with an outer casing, of a tubular spindle mounted for rotation in said casing, and comprising separable members, a chuck mounted in said spindle, and a lever, seated in said spindle to detachably secure the members thereof in relatively-fixed position, and arranged to operate said chuck, substantially as set forth. ⁷⁰

2. In a handpiece, the combination with an outer casing, of a tubular spindle mounted for rotation in said casing, and comprising separable telescoping members, means to prevent relative rotation of said separable spindle members, and detachable means, distinct ⁸⁰ from said spindle members, to prevent relative longitudinal movement thereof, substantially as set forth.

3. In a handpiece, the combination with an outer casing, of a tubular spindle mounted for rotation in said casing, mechanism to clamp an instrument in said spindle; comprising a lever mounted to rotate with said spindle, a ring g , arranged to encircle said spindle and said lever, and to rotate therewith, and a normally-stationary sleeve G , mounted to slide within said casing in operative relation with said ring, substantially as set forth. ⁸⁵

4. In a handpiece, the combination with a tubular spindle, of a sleeve A^2 , in which said spindle is journaled, an exterior casing, comprising separable members A , A' , respectively in adjustable relation with said sleeve, and means to adjust and secure said casing members with respect to said sleeve, substantially as set forth. ⁹⁵

COMEGYS C. LUSBY.
